UNITED STATES PATENT OFFICE.

HARRY M. PFLAGER AND JAMES C. TRAVILLA, JR., OF ST. LOUIS, MISSOURI, AS-
SIGNORS TO COMMONWEALTH STEEL COMPANY, OF ST. LOUIS, MISSOURI, A COR-
PORATION OF NEW JERSEY.

LOCOMOTIVE BED.

Application filed December 7, 1925. Serial No. 73,603.

Our invention relates to railway rolling stock and consists in an improved locomotive bed or frame structure.

The main object of our invention is to provide a locomotive bed possessing a high degree of rigidity and durability without any undue increase of material and weight. Preferably this improved bed consists in a one-piece casting having a number of parts formed integrally which have hitherto been added to the frame separately. We are aware that it has been suggested previously that frames of this type be formed of a one-piece casting and such a frame is described in the copending application of H. M. Pflager, one of the parties hereto, Serial Number 753,277 filed December 11, 1924, patented December 22, 1925, No. 1,566,423. However, there have been instances in the manufacture of one-piece frames of great length, which while the same would possess sufficient strength to carry their normal load and to withstand such buffing and pulling stresses as are encountered in normal use, they would not always withstand being lifted by crane chains or similar means attached to their ends only, and an object of our present invention is to so form the frame that this weakness may be overcome. Briefly, we attain these objects by making the frame box-shape in cross section with the outer walls of the box forming the outer sides of the frame and extending in a straight line from the front end of the frame to the rear end of the cradle.

In the accompanying drawings illustrating a selected embodiment of our invention—

Figure 1 is in part a top view and in part a longitudinal horizontal section taken on line 1—1 of Figure 2.

Figure 2 is a vertical longitudinal section taken on line 2—2 of Figure 1.

Figure 3 is a side elevation of the frame with the driving wheels indicated in broken lines.

Figures 4, 5, 6, and 7 are sections taken, respectively, on lines 4—4, 5—5, 6—6, and 7—7 of Figure 1, Figure 7 also showing a driving axle and wheel with its box, spring saddle and spring support.

The main frame or bed comprises side frames 1, top walls 2, and bottom walls 3

which form a box section substantially throughout the length of the frame. At intervals suitable openings are provided in each of these walls to lighten the same without unduly reducing the strength thereof. It will be noted that the side walls 1 extend rearwardly beyond the end of the bed proper to form the cradle portion of the frame and are united at their rear ends with transverse elements forming the foot plate 4, drawbar pocket 5, and corresponding parts.

At each of the driving axles, the height of the side walls is greatly reduced but to compensate therefor the walls are thickened at these points as indicated at 6 and the side walls 1 are supplemented by additional longitudinal vertical walls 7 parallel with and spaced inwardly from the side walls and cooperating therewith to form the pedestal portions of the bed.

At these portions of the bed, the upper and lower walls of the same are provided with vertical openings adjacent inner wall 7, each of which openings is adapted to receive one leg of an inverted U-shaped spring saddle 8 which straddles the side of the bed and is carried on the driving box 9. This arrangement increases the clearance between the driving wheels 10 and the frame and as there is no portion of the frame between the wheels and the springs 11 the application and inspection of the latter are facilitated.

In the structure just described, we prefer to provide integral equalizer fulcrums 12, brake hanger brackets 22, equalizer hanger lugs 13, boiler support brackets 14, cylinder brackets 15, and boiler saddles 16. These and various other elements which are usually formed separately and assembled with the frame may be cast at the same time as the body of the frame and the labor and material necessary for assembly is eliminated. This construction has the additional advantage of maintaining the rigidity of the parts and their spacing from each other which cannot be relied upon when the parts are riveted or bolted together.

Transverse partitions or walls are provided on the interior of the box-shaped frame at 17 and serve to reinforce the side walls 1 and the supplementary walls 7.

- Other transverse partitions 18 are provided between the ends of the supplementary walls 7 and serve to brace the side walls at such points.
- Obviously these and other details of our invention may be modified or even eliminated without departing from the broad idea of the box-shaped bed having the characteristics referred to. It will be noted that 10 the construction described eliminates any offsets in the side wall of the frame, thereby reducing the stresses due to the eccentricities of buffing loads.
- Another type of boxshape underframe is 15 shown in the copending application of H. M. Pflager Serial No. 71,640 filed November 27, 1925, and in this application, as well as in the Pflager patent referred to in the first part of the specification, it is proposed to 20 form the steam cylinders and supply chests integrally with the side of the frame. It will be understood that a similar arrangement of the steam cylinders and supply chests could be provided on the present 25 frame although such is not illustrated in the drawings, the latter showing the forward ends of the frame adapted to mount detachable cylinders in the usual manner.
- Various other modifications in the structure described may be made without departing 30 from the spirit of our invention as expressed in the claims.
- We claim:
1. A locomotive bed of box cross section 35 with its side walls substantially straight from end to end.
  2. A locomotive bed, including an integral cradle, said bed and cradle each being of box-shape cross section with their respective side walls aligned and extending in 40 a substantially straight line from the front end of the frame to the rear end of the cradle.
  3. A locomotive bed of box cross section 45 with inner vertical walls spaced from and paralleling its outer walls and cooperating therewith to form pedestals for the locomotive driving boxes.
  4. A locomotive bed of box cross section 50 with inner vertical walls spaced from and paralleling its outer walls, and transverse vertical walls connecting said inner walls on opposite sides of the bed.
  5. A locomotive bed of box cross section 55 with inner vertical walls at intervals spaced from and paralleling its outer walls, and transverse vertical walls connecting said side walls between the ends of said inner walls.
  6. A locomotive bed of box cross section 60 with inner vertical walls at intervals spaced from and paralleling its outer walls, transverse vertical walls connecting said inner walls on opposite sides of the bed, and trans- 65 verse vertical walls connecting said outer walls between the ends of said inner walls.
  7. A one-piece casting comprising a locomotive bed box shape in cross section with each side wall extending in a straight line from end to end. 70
  8. A one-piece casting comprising a locomotive bed box shape in cross section with each side wall extending in a straight line from end to end and with supplementary vertical walls parallel with and spaced inwardly from said side walls. 75
  9. A one-piece casting comprising a locomotive bed box shape in cross section with each side wall extending in a straight line from end to end and with supplementary vertical walls at intervals paralleling and spaced inwardly from said side walls, and transverse vertical walls connecting said side walls between said supplementary walls. 80
  10. In a locomotive, a bed of box cross section with its side walls substantially straight from end to end and overlying the driving boxes. 85
  11. In a locomotive, a bed having a side wall and a spring saddle straddling said side wall and provided with a spring bearing surface. 90
  12. In a locomotive, a bed box shape in cross section with a side wall overlying a driving box, there being an opening in the top and bottom wall of the bed near its side wall, and a spring saddle straddling said side wall with its inner leg extending through said opening. 95
  13. In a locomotive, a bed box shape in cross section with a side wall reduced in depth at intervals to provide openings for the driving boxes, there being openings in the top and bottom walls of the bed adjacent said reduced portion of the side wall, and spring saddles each straddling said side wall with its inner leg projecting through said openings to a point below the bottom of the reduced portion of the side wall. 100
  14. In a locomotive, a bed box shape in cross section with a side wall overlying a driving box, there being an opening in the top and bottom wall of the bed near its side wall, a spring saddle straddling said side wall with its inner leg extending through said opening, and a vertical wall on said bed paralleling and spaced inwardly from said side wall adjacent to said saddle. 110
  15. In a locomotive, a bed of box cross section with its side walls substantially straight from end to end and overlying the driving boxes, and equalizer fulcrums formed integrally with said walls between the driving boxes. 120
  16. In a locomotive, a bed of box cross section with its side walls substantially straight from end to end and overlying the driving boxes, and brake hanger fulcrums formed integrally with said walls between the driving boxes. 125

17. In a locomotive, a bed of box cross section with its side walls substantially straight from end to end and overlying the driving boxes, and equalizer fulcrums formed integrally on the inside of said walls between the driving boxes and brake hanger fulcrums formed integrally on the outside of said walls between driving boxes.
18. A locomotive bed, box-shape in cross section with each side wall extending substantially in a straight line from end to end and forming a steam cylinder mounting
19. In a locomotive, a journal box, an inverted U-shaped member resting on said box, a spring mounted on said member, and a bed supported by said spring and extending through said U-shaped member.
- In testimony whereof we hereunto affix our signatures this 27 day of November, 1925.

H. M. PFLAGER.
JAS. C. TRAVILLA, JR.
